UNITED STATES PATENT OFFICE.

JOSEPH LEDWINKA, OF PHILADELPHIA, PENNSYLVANIA, ASSIGNOR TO TRACKLESS TROLLEY COMPANY OF AMERICA, A CORPORATION OF NEW YORK.

TROLLEY-POLE.

1,099,384.

Specification of Letters Patent. Patented June 9, 1914.

Application filed September 27, 1909. Serial No. 519,849.

To all whom it may concern:

Be it known that I, JOSEPH LEDWINKA, a subject of the Emperor of Austria-Hungary, residing at Philadelphia, in the county 5 of Philadelphia and State of Pennsylvania, have invented a new and useful Trolley-Pole, of which the following is a specification.

My invention relates to improvements in 10 trolley poles, and more particularly to trolley poles adapted to be used on trackless trolley systems, wherein two conducting wires are used, one to supply current and the other to return the current to the source 15 of supply.

In trackless trolley systems, the propelled vehicles run upon the streets and do not use car tracks. In such systems it is necessary that when two propelled vehicles meet, 20 using the same set of overhead wires and going in opposite directions, the trolley pole of each vehicle must be transferred from one to the other, as the current collector or carrier cannot pass each other.

One of the objects of my invention is 25 to provide a trolley pole that can be easily and quickly transferred from one car to another, and the circuit established between the conducting wires and the car motor.

Another object is to provide a trolley pole 30 that will disconnect itself instantly from its fastenings should the overhead trolley or carrier be caught in the overhead wires.

Another object is to provide a safety device 35 that will hold the pole in place, but will allow the pole to be disconnected whenever the pull exceeds a certain limit.

Another object is to provide a swivel-socket device, whereby the pole can be 40 swung in a circle without breaking the electric circuit.

Further objects will more definitely appear from the detailed description to follow.

The invention is clearly defined and 45 pointed out in the claims.

A structure embodying the features of my invention is illustrated in the accompanying drawings, forming a part of this application, in which—

50 Figure 1 is a view in perspective of my improved trolley pole, as attached to an electric vehicle. Fig. 2 is a view, partly in section, of the trolley pole and the swivel device in which contact is made. Fig. 3 is

a top view of the safety device, and a cross 55 section of the pole *in situ*. Fig. 4 is a longitudinal section of the swivel socket and its fastening means.

Similar letters of reference refer to similar parts throughout the several views. 60

The drawings illustrate my improved trolley pole as adapted for use on a trackless trolley system. As shown, 1 represents the trolley pole, preferably made of lined conduit-pipe to accommodate the conducting wires 2, 2 passing therethrough. In the preferred form of my invention, the lower end of the pole is provided with a coupling 3 adapted to receive and hold the metallic contacts 9 and 10, which are connected with the wires 2, 2. These contacts are circular (see Fig. 4), the lower ends of each being provided with slots (not shown) to admit of their contraction and expansion. The contacts are separated from each other and held in place by suitable insulation 11. The coupling 3 is adapted to receive a socket 4, provided with a swivel joint 8, and secured to the vehicle body 7 by the bracket 12. The socket 4 is provided with metallic contacts 13, 14. The contact 13 is circular, having slots 15, 15 therein to permit of its expansion or contraction, and is adapted to receive the contact 9. The contact 14 is round and provided with a 70 slot 16 to permit of its insertion in the contact 10. The contacts 13, 14 are also suitably separated from each other and held in place by insulation 17, and they are connected respectively to the motor circuit 75 wires, 18 19.

To the upper end of the pole 1 is secured a funnel-shaped L 20, which prevents the wires 2, 2 leading therefrom from cutting on the edge. The upper end of the pole and the L are provided with rubber plugs 21, 21 through which the wires 2, 2 pass to hold the wires in place and make the construction waterproof. Secured to the upper end of the pole by a suitable clamp 22 is the flexible steel cable 23 leading to the trolley carrier or wheel. This steel cable is to take the pulling strain in case the trolley carrier or wheel should get caught in the overhead construction. Both wires 2, 2 and cable 23 105 are suitably taped to insure waterproof construction.

In order to maintain the pole in place and

prevent its displacement from its normal position, should it be subjected to pulling strains, I provide a safety device 24, consisting of a flat spring 25 bent over upon itself and shaped to encircle the pole 1, while the ends 26, 26 of the spring 25 are bent outwardly in order to facilitate and guide the entrance of the pole. Tension of the spring 25 around the pole is maintained by means 10 of the tension adjusting mechanism consisting of a threaded screw 27, the nut 28 and the coiled spring 29. By means of this tension-adjusting mechanism any required tension on the pole 1 can be maintained so that 15 the pole cannot be pulled out unless the pulling strain exceeds a definite amount. The spring 25 is secured to the vehicle body 7 by the circular clamp 30 adapted to engage the rod 31 of the body 7. Any other suitable securing means may, however, be used.

In the preferred embodiment of my invention, I provide a device to keep the pole 1 in the socket 4 so as to maintain good electrical connections between the contacts. 25 This device consists of a downwardly-extending finger or member 32 secured to the pole 1 by the bracket 33, the finger 32 being adapted to pass under the extension 34 secured to the body 7 by the bracket 35. If 30 the pole should be drawn out of and released by the safety device 24, it would take the position indicated by the dotted lines in Fig. 1. If the pole were righted and replaced in the safety device, the finger 32 would pass 35 under the extension 34, thereby forcing the pole into the socket 4 and establishing good electrical connections therein.

It is apparent that while I have shown and illustrated a trolley pole adapted for 40 use on a trackless trolley system, it is capable of being constructed for use on ordinary street railway cars, without departing from the spirit of my invention.

What I claim as new, and desire to secure 45 by Letters Patent, is:

1. In combination, a support, a trolley pole pivoted to said support, and means for normally maintaining said trolley pole in a predetermined position with respect to said 50 support, said maintaining means being adapted to be released when an undue pressure is exerted upon said trolley pole in a direction to tilt the same about its pivot.

2. In combination, a support, a trolley pole connected to said support so as to be capable of being swung about the same, and means for normally maintaining said trolley pole in a predetermined position with respect to said support, said maintaining 60 means being adapted to be released when an undue pressure is exerted upon said trolley pole in a direction to swing the same with respect to said support.

3. In a trolley pole system, the combination 65 with a trolley pole, of a socket to re-

ceive said pole, a safety device engaging said pole to prevent its disengagement from said socket, and means coöperating with said safety device for pre-determining the pressure of said device upon the pole to maintain said pole in normal position. 70

4. The combination with a pivoted trolley-pole, of a safety device engaging said pole to maintain said pole in its normal operative position, said safety device being 75 adapted to release said trolley pole when an undue pressure is exerted upon the same in a direction to tilt the trolley pole about its pivot, and a tension mechanism coöperating with said safety device for pre-determining 80 the pressure of said device upon said pole to maintain it in said normal operative position.

5. The combination with a trolley-pole, of a propelled vehicle, a socket carried 85 thereby to detachably receive the lower end of said pole, and means for maintaining said pole in said socket while the pole is in its normal operative position, but permitting said pole to be released from said socket 90 when said pole is moved out of its normal operative position.

6. The combination with a trolley-pole, of a propelled vehicle, a socket carried thereby to detachably receive the lower end 95 of said pole, and a locking device for insuring good electrical connection between said pole and said socket when the pole is in its normal operative position, but permitting said pole to be released from said socket 100 when said pole is moved out of its normal operative position.

7. The combination of a trolley-pole, of contacts carried by the lower end of said pole, a propelled vehicle, a socket carried 105 thereby to detachably receive the lower end of said pole, contacts in said socket, and a locking device for insuring electrical connection between said contacts when the pole is in its normal operative position, but permitting 110 said pole to be released from said socket when said pole is moved out of its normal operative position.

8. The combination with a trolley-pole, of a socket carried by the lower end of said pole, a propelled vehicle, a socket carried thereby to detachably receive said first socket 115 to establish electrical connection between said vehicle and pole, and means for locking said pole in said second socket when said pole is in its normal operative position, but permitting said pole to be released from said socket when said pole is moved out of its normal operative position.

9. The combination with a trolley-pole, of a socket carried by the lower end of said pole, a propelled vehicle, a socket carried thereby, said sockets being adapted to detachably engage each other to establish electrical connections there between, and a lock. 120 125 130

ing device to maintain said sockets in electrical contact while said pole is in its normal operative position, but permitting said pole to be released from said socket when said 5 pole is moved out of its normal operative position.

10. The combination with a trolley-pole, of a socket carried by the lower end of said pole, a propelled vehicle, a pivoted socket carried thereby, said sockets being adapted 10 to detachably engage each other to establish electrical connections there between, means for automatically locking said sockets in electrical contact upon the placing of said 15 pole in normal operative position, and means

engaging the said pole to maintain it in said normal operative position.

11. The combination with a trolley pole, of a propelled vehicle, a socket carried thereby to detachably receive the lower end 20 of said pole, and means for automatically locking said pole in said socket upon the placing of said pole in normal operative position.

In testimony whereof, I sign this specification in the presence of two witnesses.

JOSEPH LEDWINKA.
